GARMENT

Carmen Larison, Phoenix, Ariz.; now by marriage
Carmen L. Graham

Application July 25, 1941, Serial No. 404,087

4 Claims. (Cl. 2—211)

The present invention relates generally to the manufacture of women's garments such as skirts, dresses or the like and relates more particularly to the manufacture of a pleated, wrinkled or crinkled skirt or dress and also to the packaging of the garment for transportation and display.

More specifically the present invention relates to the manufacture of a skirt or dress having more or less irregular pleats or wrinkles lengthwise of the garment; the invention having for one of its objects a method which greatly facilitates the production of closely spaced numerous and irregular pleats or wrinkles disposed generally lengthwise of the garment and which impart to the garment a particularly attractive appearance by virtue of the great number of such pleats, wrinkles or creases, and also by virtue of their irregularity.

Another object of the invention is to provide a garment of this type in which the creases, though extending generally lengthwise of the garment, do not each necessarily extend the full length of the garment. By the present method some creases may stop short of the length of the garment at irregular points, but other creases also extending generally lengthwise of the garment then proceed from these points at perhaps a slight angle to the first mentioned creases. This arrangement of creases, pleats or wrinkles imparts to the garment a fulness of a highly distinctive quality. The present process is particularly applicable to garments made of cotton prints by reason of the attractive ornamental appearance obtained by the interplay of the print design with the irregular crease, wrinkles or pleats; moreover, the garment of the present method by reason of the multiplicity and irregularity of the lengthwise creases minimizes the effects of the creases had during wear of cotton prints, and the garment therefore retains its attractive and fresh appearance for a much longer period than other cotton garments.

Another object of the present invention is to provide an attractive and compact package including the garment of the present manufacture, which prevents the introduction of undesirable creases in the garment, which greatly facilitates the storing and transportation of the garment and which in addition also forms a novel and attractive display of the garment in the store and ready for delivery to the customer.

Under the present invention the full gathered skirt is soaked in water and while still wet it is wrapped tightly around a stick, tied with several cords and permitted to dry. In the wrapping

operation care is taken that the garment is creased so as to have each portion of the gathered material extend lengthwise of the stick and below the corresponding portion of the waist band. By means of this step the creases, though irregular in length and direction, nevertheless all extend in a general direction substantially parallel to the stick, and in the garment when worn the creases extend downwardly from the waist band. When the wrapping operation is completed, the exposed folded edge extends substantially parallel to the stick.

The wet wrapped skirt may be dried in any suitable manner as by exposure to the atmosphere or by exposure to warm air. When dry, the skirt wrapped and tied on the stick is ready for storage, transportation and display to the trade and consumer, and for delivery to the trade and consumer. It forms its own package which constitutes a highly attractive display of the garment. Moreover the garment can be delivered to the purchaser in this form without unwrapping it from the stick. Thus the problem of packaging and delivery of the garment to the purchaser is simplified.

Other advantages of the present invention will become apparent to persons skilled in the art from the accompanying drawing and the following specification.

30 In the drawing:

Fig. 1 shows the customary full gathered skirt;
Fig. 2 shows the first step of the wrapping operation;

Fig. 3 shows the completed wrapped skirt;
35 Fig. 4 shows a modification in which a wrapping of any suitable material is employed in lieu of the cords shown in Fig. 3; and

Fig. 5 illustrates the appearance of the skirt when unwrapped for wear.

40 Referring to the drawing, Fig. 1 shows a full gathered skirt made in the customary manner. This comprises the waist band 10 and the main body portion 11. The length of the waist line of the portion 11 before it is gathered and attached to the waist band should preferably be approximately twice the length of the waist band. The skirt 11 is fully gathered as it is sewed to the waist band to form a multiplicity of closely spaced gathers 12. These cause the formation of a relatively small number of uncreased folds 13 which extend downwardly to the hem of the skirt.

45 In the next step in the process, the skirt is dipped in cold water so that it is thoroughly wet. After permitting the excess water to drip off, it is wrapped on a stick 14. For this wrapping opera-

tion one end of the waist band 10 is fixed to the stick by a tack 15. The folded edge 16 is then made to lie lengthwise of the stick 14 and extend downwardly substantially in line with the tacked edge of the waist band 10. As the wrapping proceeds care is always taken that the gathered portions and drapes 13 should extend substantially parallel to the stick and that the drapes should be in approximate alinement with the gathers 12 from which they flow. Thus in this process of wrapping, the material between the drapes 13 is bunched together closely and tightly compacted and made to lie closely to the stick or to the layer of material immediately beneath. In this process of wrapping, the uncreased drapes 13 tend to disappear and are replaced by a great multiplicity of irregular, closely spaced and generally longitudinal creases which are approximately parallel to the stick. Such creases are indicated at 17 in Figs. 3 and 5. It should be particularly noted that the number of such creases is many times greater than the number of drapes or uncreased folds that normally occur in a gathered skirt and that the creases greatly exceed the number of gathers at the waist band.

Many of the creases originate with the gathers and many more creases are also disposed in the material between the gathers. Many creases appear to terminate at irregularly disposed points as at 18 and 19 while other creases that may have originated above these points continue from the points 18 and 19 downwardly. Some of the creases commence at irregular points below the waist line; but all creases extend generally downwardly even though they may vary somewhat in direction.

As throughout the wrapping operation, so at the end thereof care is taken that portions of the skirt 11 that are creased and bunched together should be made to lie in line with the corresponding gathers and that the exposed folded edge 20 should be in substantial alinement with the exposed folded edge 21 of the waist band and be disposed approximately parallel to the stick.

When the wrapping is completed the cords 22 are tied around the skirt as shown, these being, preferably, four such cords, one near the waist band, another near or about the hem of the skirt, and two more about evenly spaced over the main body portion of the skirt 11. These hold the creased wet skirt closely wrapped to the stick. The skirt thus wrapped and tied on the stick will cause the creases to be accentuated during the drying operation. For drying the skirt thus wrapped and tied, it is merely exposed to the atmosphere or to the flow of warm air.

When dried, the skirt wrapped and tied to the stick is ready for the market, is displayed in this form to the trade and to the public and is also transported and delivered in this form to the trade and to the public.

If desired, the wrapped skirt may be enclosed in a protective covering 23, which has its edges held together by pins 24. In this form the cords 22 may or may not be employed under the covering 23 as desired.

Fig. 5 illustrates the appearance of the skirt when worn by the purchaser, and it will be observed that the irregular and closely spaced creases impart to the skirt the desired fullness and a particularly distinctive appearance. In addition these irregular creases serve to minimize

the effect of the creases ordinarily had when such skirts are worn and that therefore the neat and fresh appearance of the garment is lengthened and its life is enhanced.

5 When both the cords 22 and a covering 23 are employed, the skirt should preferably be dried before the covering 23 is applied. If desired, the cords 22 may be eliminated and the covering 23 applied and its edges secured together by pins 24 10 while the skirt is still wet and the package thus formed is then dried by exposure to the atmosphere or to warm air.

I claim:

1. A method for the simultaneous creasing and packaging of a skirt or the like having a fully gathered waist line, and having downwardly directed uncreased drape-like folds, comprising wetting the skirt, tightly forming a multiplicity of downwardly extending creases in substantial alinement with the corresponding gathered portions and simultaneously wrapping said wet skirt exclusively on a stick with the creases extending substantially parallel to the stick, encircling at least portions of the skirt so that the stick and wrapped skirt form a compact package, and drying the skirt.

2. A method for the simultaneous creasing and packaging of a skirt or the like having a fully gathered waist line, and having downwardly directed uncreased drape-like folds, comprising wetting the skirt, tightly forming a multiplicity of downwardly extending creases in substantial alinement with the corresponding gathered portions and simultaneously wrapping said wet skirt exclusively on a stick with the creases extending substantially parallel to the stick, tying the creased wet skirt to the stick circumferentially at several points along the length of the skirt, so that the stick and wrapped skirt form a compact package, and drying the skirt.

3. A method for the simultaneous creasing and packaging of a skirt or the like having a fully gathered waist line, and having downwardly directed uncreased drape-like folds, comprising wetting the skirt, tightly forming a multiplicity of downwardly extending creases in substantial alinement with the corresponding gathered portions and simultaneously wrapping said wet skirt exclusively on a stick with the creases extending substantially parallel to the stick, tying the creased wet skirt to the stick circumferentially at several points along the length of the skirt, so that the stick and wrapped skirt form a compact package, wrapping the dried skirt in a piece of fabric and securing the edges of the fabric together.

4. A method for the simultaneous creasing and packaging of a skirt or the like having a fully gathered waist line, and having downwardly directed uncreased drape-like folds, comprising wetting the skirt, forming a multiplicity of downwardly extending creases in substantial alinement with the corresponding gathered portions and simultaneously wrapping said wet skirt exclusively on a stick with the creases extending substantially parallel to the stick, covering the skirt with a piece of fabric, securing the edges of the fabric together, and drying the package thus formed.

CARMEN LARISON.
